PACKAGE

John M. Ducey, Washington, D. C., assignor of forty-eight per cent to Bryan Mack, Washington, D. C.

Application November 17, 1941, Serial No. 419,508

15 Claims. (Cl. 206—41.2)

The present invention relates to an improved package or container for cigarettes and similarly shaped articles.

Despite the many objectionable features in the popular package of cigarettes, very little effort has been expended to improve its shape and construction. Such a package is still bulky, wasteful, and cumbersome to handle. It is also very inconvenient to open, and when once opened, no means are provided to protect the cigarettes remaining in the package from becoming loose, bent, broken, twisted, torn, or crushed. Moreover, the package is usually made of materials which provide very little protection from the detrimental effects of exposure to air, moisture, and dirt, with the result that the smoker fails to obtain the full flavor, quality, and quantity of the tobacco in the cigarettes.

Among the important objects of the invention are to provide a package for cigarettes and similarly shaped articles, which is handy and neat to carry, which is easily opened to permit the cigarettes to be singly removed; which has means for maintaining the cigarettes remaining in the package in a firm and compact position at all times, and which fully protects them from being damaged or contaminated by exposure to air, moisture, or dirt.

A further object consists in forming a cigarette package from a pre-formed blank folded to provide closed sides and ends, and having a partition between the front and rear sides to form separate compartments in which the cigarettes are arranged lengthwise or transversely in rows extending from the bottom to the top of the package. The front and rear sides of the package are provided with transverse and vertically spaced weakened portions to form bendable and detachable sections, and each weakened portion is disposed substantially in alignment with the plane of contact between two adjacent cigarettes. Each section in the front and rear sides of the package adjacent the top or cover is initially movable outwardly to allow withdrawal of the uppermost cigarette and then may be bent inwardly to overlap the cigarette below the one removed in order to insure the remaining cigarettes being kept firm, fresh, and compact. Each of the sections constituting the front and rear sides of the package is detachable when the cigarette immediately below the same is withdrawn so that each of these sides is gradually reduced in size as the cigarettes are removed.

Another object consists in providing a package for cigarettes from a blank folded to provide a

main compartment in which the cigarettes are disposed lengthwise or horizontally in rows extending from the bottom to the top of the package so as to be removable laterally from one side thereof, and in which one or both of the opposite sides of the package may be provided with an auxiliary compartment or compartments extending from the bottom to the top of the package, and in which the cigarettes are arranged endwise and are removable without disturbing the cigarettes in the main compartment.

15 A further object consists in associating with the main package, an auxiliary package formed from the same blank of material and detachably connected thereto, the main package being arranged to carry cigarettes of standard size or smaller, which are transversely or lengthwise positioned therein so as to be removed singly from the front and rear sides, while each auxiliary package preferably accommodates cigarettes of larger or "King's size" removable endwise from the top of the package.

Other objects and advantages of the invention will become apparent from the following description, when taken in conjunction with the accompanying claims and drawings.

Referring to the drawings, in which are shown several preferred embodiments of the invention:

Figure 1 is a plan view of a blank cut and shaped to form a package in accordance with the present invention;

Figure 2 is a perspective view, showing an intermediate step in the forming of the package from the blank;

Figure 21 is a perspective view of a package formed from the blank shown in Figure 16 and showing sections removed from the front thereof;

Figure 22 is a plan view of a blank cut and shaped to form a further modification;

Figure 23 is a perspective view of an intermediate step in forming a package from the blank shown in Figure 22;

Figure 24 is a transverse sectional view of a package made from the blank shown in Figure 22;

Figure 25 is a vertical sectional view of the auxiliary package, formed from the blank shown in Figure 24;

Figure 26 is a vertical sectional view of the main package, formed from the blank shown in Figure 24, and

Figure 27 is a perspective view of the package, formed from the blank shown in Figure 22, with the cover flaps opened.

Referring to the drawings, in which like numerals indicate like parts in the several views, and more particularly Figure 1, 10 designates a blank of any suitable material, such as cardboard or the like, from which the package or container is formed. The blank 10 is initially cut and shaped to provide a rectangular portion 11 which is connected to a symmetrically-shaped portion 12 by a narrower portion 13. The portion 11 preferably constitutes the front of the package or container, while the portion 12 forms the rear thereof. Extending laterally from the outer sides of the portions 11 and 12 are wings 14 and 15 respectively, which are of substantially the same width as the portion 13 with which they coact to form the opposite sides or ends when bent at right angles to the front and rear sides of the package. The portion 11 has extending

downwardly therefrom a portion 16 positioned between a flap 17 on the portion 13 and a flap 18 extending from the wing 14. The lower end of the portion 11 at the juncture of the portion 16 therewith is scored or creased as at 19 to align with a transverse score line 20 on the wing 14 and the score lines 21 and 22 on the portions 13 and 12 respectively. The portion 16 is of greater length than the portion 11 and is provided with the spaced score lines 23 and 24 to form the auxiliary bottom 25 and the flange 26 (Figure 2). The flange 26 may have side flaps 27 arranged to be bent to extend downwardly therefrom to provide means for further assisting in maintaining the cigarettes compact in the package. The upper end of the portion 11 has a medially disposed hinged tab 28. The portion 12 below the score line or hinge 22 has a flap 29 which forms the main bottom of the package when the latter is made up. The upper end of the portion 12 is connected by a transverse score line 30 to a flap 31 which forms a closure or cover for the top of the package. The flap 31 has extending from opposite sides thereof, the wings 32 and 33, and is provided with a hinged portion 34 having a medially disposed tab 35. The portion 34 overlaps the front 11 and the tab 28 when the package is assembled and may be removably secured to the front by adhesive means to assume the closed position shown in Figure 4. The flap or cover 31 has perforations 36 arranged to be punched out to form a tab 36 connected to the side 12 to facilitate access to the inside of the package.

The portions 11, 12, and 13 and the wings 14 and 15, as well as the flap or cover 31, are provided with transverse weakened portions or perforations 37 spaced vertically along the blank 10 to provide bendable and detachable sections 38 in the front, rear, top, and bottom of the package. The portion 13, wings 14 and 15, and the flaps 17, 18, 32, and 33 have vertically disposed weakened portions 39 which coact with the transverse weakened portions 37 to permit the sections 38 to be flexed and be detached from the package to reduce the size of the front 11 and rear 12 as the cigarettes are individually and laterally removed.

The weakened portions 39 intersect the transverse weakened portions 37 so as to divide the opposite ends 13 and 14-15 in substantially square sections 38' (Figure 3) which normally engage the ends of the adjacent cigarettes to prevent lengthwise displacement thereof in the package. The blank 10 is also formed with spaced vertical creases or score lines 40, 41, 42, and 43 for folding the sides of the package to their proper shapes. The top flap or cover 31 has vertically spaced creases 44 to allow the wings 32 and 33 to be bent downwardly along the adjacent sides of the package when the latter is closed.

To make up the closed flat package shown in Figure 4, the blank 10 is folded on its transverse and vertically disposed score lines to form the front 11, rear 12, and the opposed sides 13 and 14-15. The portion 16 is flexed along the line 19 to form the auxiliary bottom 25 (Figure 2) and along the line 23 to provide a partition 45 extending upwardly and substantially parallel with the front 11 to form a compartment 46 therebetween. The partition 45 also coacts with the rear side 12 to form the compartment 47. The main bottom 29 is then moved to overlap the adjacent auxiliary bottom 25, and the wings

17 and 18 are folded over the bottom and adhesively connected thereto. The wing 14 now overlaps the wing 15 and is secured thereto by adhesive to form with the portion 13, opposite ends of the package. The parts now assume the position shown in Figure 3. The front compartment 46 and the rear compartment 47 are then filled with cigarettes 48 (Figure 5), and the flange 26 on the free end of the partition 16 is preferably bent inwardly or in a direction opposite to that of the auxiliary bottom 25, so as to overlap the uppermost cigarette in the rear compartment 47, and the flaps 27 on the flange 26 are bent downwardly in order to assist in maintaining the cigarettes in the compartment 47 in a compact position. If desired, the compartment 46 may first be filled with cigarettes, and after the rear portion 12 is moved in substantial parallelism with the front portion 11 and the bottom 29 and wings 17 and 18 adhesively connected, the rear compartment 47 may be filled and the flange 26 and flaps 27 bent to maintain the cigarettes compactly and firmly in the compartment 47, or the cigarette may be fed to the compartments by a machine. The cover 31 is then folded over the top of the package, and the wings 32 and 33 bent downwardly so as to be adhesively connected to the adjacent sides 13 and 14—15 respectively. The portion 34 of the cover 31 is moved to overlap at least the upper section 49 of the front 11 and may be secured thereto by a light adhesive, so that when the package is closed, the parts assume the position shown in Figure 4, with the tab 35 conveniently positioned to move the flap 34 away from the front 11.

The blank 10, from which the package is formed, may be of any high-grade strong and durable material, such as cardboard or the like, and preferably has one side which ultimately constitutes the inside face of the package, treated with a special lacquer having a tobacco flavor and color so as to displace the use of tinfoil, and which acts as a protection against dirt and moisture. Both sides of the blank 10, in forming the package, may have secured thereto by a suitable adhesive, a layer of Cellophane 50 (Figure 2a) shaped to conform to the cut and fold of the particular design of the package. The Cellophane within the package provides means for rendering the cigarettes impervious to air and moisture and is assisted in this purpose by the Cellophane covering the outside of the package.

It will be seen that when the blank 10 is formed into the closed package, the partition 45 provides the spaced compartments 46 and 47 of such width and length as to insure the cigarettes 48 being firmly and compactly held in position without danger of becoming loose or broken. The cigarettes 48 are arranged transversely or lengthwise in the compartments and extend from the bottom to the top of the package in two vertical rows or layers. The transversely disposed weakened portions 37 in the sides of the package are spaced so that each weakened portion will be substantially in alignment with the plane of contact between two adjacent cigarettes (Figure 5), and the Cellophane wrapper adjacent the weakened portion is perforated to be removable with the front and rear sections 38 of the package. As best shown in Figures 7 and 8, the length and width of the bendable and detachable sections 38 are such as to allow each section to cover and protect the uppermost cigarette in each of the compartments 46 and 47 when a cigarette is removed therefrom.

The flap 28 hinged to the upper section 49 of the front of the package and the flap 36' connected to the upper section of the rear of the package, provide means for initially obtaining access to the front and rear compartments 46 and 47 respectively, so as to withdraw singly the cigarettes therefrom. The tab 28 is normally concealed by the flap 34 on the cover 31 so that upon raising the flap 34 by the tab 35, the tab 28 may be grasped, and upon subsequently tearing the section 49 along the vertical score lines 39, the section 49 may be flexed outwardly along its transverse weakened portion 31 to permit the withdrawal of the uppermost cigarette from the compartment 46. The section 49 is then flexed inwardly to overlap and cover the cigarette immediately below the one removed so that the uppermost section now assumes a position similar to that shown in Figure 7, in order to insure the cigarettes remaining in the package being maintained compact and free from contamination and the destructive effects of air, moisture, and dirt.

The cigarettes 48 are preferably singly and laterally withdrawn first from the compartment 46 so as to gradually reduce the size of the front 12 of the package (Figure 7) until it has been completely exhausted, and then the cigarettes in the rear compartment 47 are individually removed and the rear side reduced until the package is empty. The front and rear faces of the partition 45 may have printed thereon any suitable advertising matter similar to what is contained on the outer surfaces of the package 11, so that when the front and rear sections are removed, the printed matter on the partition may be available to identify the maker and contents of the package.

When the cigarettes have been withdrawn from the front compartment 46, the package is turned, and the flap 36 in the cover 31 is forced outwardly so as to be operable in substantially the same manner as the flap 28 to permit the removal singly of the cigarettes from the rear compartment 47 in substantially the same manner as the cigarettes are withdrawn from the front compartment. In each instance it will be noted that the uppermost section 38 is bent over the top cigarette so as to protect the same. The transverse and vertical weakened portions in the opposite sides 13 and 14—15 of the package form the square detachable end sections 38' which, when the aligned transverse section 38 is bent over the uppermost cigarette, may be moved to overlap the same, or the sections 38' may remain in their original vertical positions so as to be detached from the package with its adjacent transverse section when the cigarette immediately below the same has been withdrawn from the package.

The package, as shown, contains twenty cigarettes, preferably of standard size, and is of elongated flat shape so as to be conveniently handled and carried in a pocket or purse. The bendable and detachable sections 38 and 38', constituting the sides of the package, provide simple, efficient, and positive means for protecting the cigarettes remaining in the package from being bent or otherwise damaged and also allows the cigarettes to be singly removed without disturbing the compact arrangement of the cigarettes remaining in the package. Manifestly, the size and shape of the package may be varied

to accommodate any number of cigarettes or similarly shaped articles of different sizes and shapes.

In the modification shown in Figure 9, the cardboard blank 52 is first cut and shaped to provide flap portions which form the front 53, rear 54, and the opposed sides or ends 55 and 56 of the main package. The rear side 54, at its lower end, is connected to a flap 57 by a crease or score line 58 so that the flap 57, when folded, constitutes the bottom of the package. The upper end of the rear side 54 has a flap 59 hinged thereto as at 60 to form the cover or closure of the package. The cover 59 has hinged wings 61 and 62 extending laterally therefrom and a flap 63 provided with a tab 64 arranged to be folded over the front of the package and adhesively secured thereto. The front and rear sides or walls, as well as the opposite ends 55 and 56, are formed with spaced transversely disposed weakened portions or perforations 65 spaced vertically to provide bendable and detachable sections 66 on the front and rear sides of the package. The opposed sides 55 and 56 and the wings 61 and 62 are also formed with vertical weakened portions 67 which divide the opposite sides or ends of the package into substantially square-shaped bendable and detachable sections 68.

The front side 53 has an extension 69 provided with the spaced transverse creases 70, 71, and 72 so that when the extension is folded along the creased lines, it forms the bottom 73 (Figure 10), a partition member 74, and a flange 75. The partition member 74 divides the main package into two spaced compartments 76 and 77 (Figure 13) in which the cigarettes 78 are arranged in two vertical rows and are disposed lengthwise or transversely of the package. The cigarettes in the compartments 76 and 77 may be of standard size or smaller, and the width of the compartment is such that in any event, the cigarettes will be maintained firmly and compactly in position.

The front 53 has extending laterally therefrom a portion 79 provided with vertical creases 80, 81, and 82 which, when folded, form the sides 83, 84, 85, and 86 of an auxiliary package or compartment 87 which is of the same length and breadth as the main package and is arranged to receive cigarettes larger than standard size and which are popularly referred to as "King's size" cigarettes. The side 83 of the auxiliary package has extending downwardly from its lower end, a portion 88 formed with spaced crease lines 89, 90, and 91, and a hinged wing 92 provided with a flap 93 projecting from its upper end. The side 84 has a depending hinged flap 94. The outer side 86 of the portion 79 is formed with a marginal flange portion 95 coextensive in length therewith. The portion 79 is preferably connected to the side 53 by a vertically disposed weakened portion 96 so that the auxiliary package 87, when formed, may be detachably connected to the main package.

In forming the main and auxiliary packages from the blank, the front, sides, and ends are folded along their respective score lines, and the extension 69 is bent to provide the partition 74 having the bottom 73 and oppositely disposed flange 75. At the same time, the portion 79 is folded along the vertical score lines in the manner as shown in Figure 10. The rear side 54 is bent inwardly so that the end 56 is positioned opposite to the end 55, and a marginal hinged flange portion 97 on the side or end 56

is bent inwardly and adhesively connected to the adjacent front side 53 as at 98 (Figure 12). The lower portion 57 on the rear side 54 is folded inwardly to form the bottom of the main package and is adhesively connected to the underside of the auxiliary bottom 73 formed by the partition 74. A hinged flap 99 extending downwardly from the side 68 is folded to overlap the bottom 57 and is adhesively secured thereto to further reinforce the lower corner portion of the package. The portion 79 is then folded along its vertical score lines, and the extension 88 is bent upwardly to divide the auxiliary package into separate compartments 100 and 101 in which the "King's size" cigarettes 102 are arranged vertically or endwise. The flap 94 is flexed so as to be adhesively connected to the bottom 57 and coats with the flap 99 to maintain the bottom in a firm position and to reinforce the same. The marginal flange 95 is folded and adhesively secured to the adjacent side 43 of the auxiliary package as at 103 (Figure 12). The parts are now in the position shown in Figure 11, with the cover open so that the main package and the auxiliary package 87 may be filled with cigarettes. When this is done, the auxiliary package 87 may be moved about its vertical hinge formed by the weakened portion 96 to allow the wings 61 and 62 to overlap the adjacent sides of the main package and be adhesively secured thereto, or the main package may be filled with cigarettes and closed by the cover 59 before completing the formation of the auxiliary package 87. The top of the auxiliary package, after the cigarettes are inserted, is closed by folding the wing 92 so that its flap 93 overlaps the side 85, in order to be secured thereto by a suitable adhesive means.

When the main and auxiliary packages are filled with cigarettes and closed, the cigarettes in the compartments 76 and 77 are arranged lengthwise or horizontally of the package, and the flange 75 on the partition 74 tends to maintain the cigarettes in the rear compartment firmly and compactly in position. The cigarettes in the main package are individually removed therefrom in substantially the same manner as in the form of the invention previously described. The front of the package may have a hinged tab 104 to facilitate the removal of the uppermost cigarette in the front compartment. Each of the sections 66, when the uppermost cigarette is removed, is arranged to overlap and protect the cigarette immediately below the same in order to prevent damage or contamination of the cigarettes remaining in the package. When the front compartment 76 has been emptied, a tab 105 formed in the top 59 may be utilized to initiate the bending of the uppermost section 66 in the rear side, to remove the adjacent cigarette. The sections 86 forming the rear side 54 also constitute protecting means for maintaining the cigarettes remaining in the package in a fresh and undamaged condition.

The auxiliary package 87, as shown, is arranged to accommodate four cigarettes separated by the partition 88, and the cigarettes therein may be individually removed endwise without disturbing the arrangement of the cigarettes in the main package. When the cigarettes are exhausted in the auxiliary package 87, the same may be detached from the main package along the weakened portion 96 so as to be separated therefrom as shown in Figure 15.

The main package is arranged to carry twenty cigarettes, either of standard or smaller size,

which are removable lengthwise or transversely of the package; while the auxiliary package 87 accommodates four cigarettes of "King's size." Thus, means are provided in which cigarettes of different sizes are packed in one container, so that the smoker, if in the habit of at certain times enjoying a long smoke, such as after meals, and at other times a shorter smoke, may be able to conveniently and economically satisfy his taste.

Figure 16 shows a blank 110 cut and shaped to form another modification in which the portions are shaped to provide the front side or wall 111, the rear side 112, and the side or end 113. A wing 114 extending laterally from the front side 111 coacts with a complementary wing 115 extending from the rear side 112 to provide the end opposite to the end 113 when the package is formed (Figure 18). The blank has vertically spaced score lines 116, 117, 118, and 119 which, when folded, form the package having a front side 111, a rear side 112, and opposed ends 113 and 114—115. The front 111 has an extension 120 formed with transverse vertically spaced creases 121, 122, and 123, which, when flexed, provide the auxiliary bottom 124, and the partition 125 between the front and rear sides, that form the spaced compartments 126 and 127. The flange 128 on the partition 125, when bent inwardly, overlaps the uppermost cigarette in the rear compartment 127 to maintain the cigarettes in this compartment firmly in position. Extending downwardly from the side or end 113 is a portion 129 having a marginal flange 130 on one side and a slightly longer flange 131 on the opposite side, and a depending flap 132. The portion 129 and its associated parts, when folded along the spaced vertical score lines 133 and 134, and the transverse spaced score lines 135 and 136 being arranged to coact with the end 113 to form one of a pair of auxiliary packages 144 (Figure 18). The wing 114 also has a depending portion 138 provided with transversely and vertically disposed score lines 139 and 140 respectively, which, when folded, provide the spaced sides 141 and 142 and the flap 143, the portion 138 then being flexed to be disposed substantially parallel to the wing 114 to coact therewith and form opposite sides of the auxiliary package 137. The rear side 112 has a hinged extension 145 which constitutes the bottom of the package. A foldable flap 146 on the side of the extension 145 overlaps and is adhesively connected to the wing 115 when the package is assembled. A hinged cover 147 extends from the upper end of the rear side 112 and has hinged wings 148 and 149 arranged to be folded over the adjacent sides or ends 115 and 113—114 and adhesively secured thereto when the cover 147 is in its closed position. The cover 147 is also formed with a hinged flap 150 having a tab 151 which normally overlaps and is adhesively connected to the front 111 of the package.

The front and rear sides of the package are provided with transverse vertically spaced weakened portions 152 and the vertically spaced weakened portions 153 which form the bendable and detachable sections 154 for permitting lengthwise or lateral removal of the cigarette individually from the compartments 126 and 127 and which, when folded inwardly, are arranged to overlap and cover the cigarette immediately below the one removed so as to protect the same. The upper section in the side 111 is formed with a tab 155, and the cover 147 may be provided with a similarly shaped tab 156 connected to the

upper section in the rear side 112 to provide means for conveniently moving the upper section in each of the front and rear sides of the package to permit individual removal of the cigarettes therefrom.

In forming the main and auxiliary packages, the blank 110 is folded along its transverse and vertical score lines to assume an intermediate position as shown in Figure 17. The sides 129 and 138 are then flexed upwardly so as to be disposed substantially parallel to the sides 113 and 114 respectively. Adhesive is then applied to the outer surfaces of the flanges 130, 131, 141, and 142 so as to connect the same to the adjacent front and rear sides of the package in order to form the spaced auxiliary packages 137 and 144. As shown, each auxiliary package is of such size and shape to accommodate two large or "King's size" cigarettes 159 arranged endwise or vertically so as to be removed from the top of the package and independently of the cigarettes in the main package. The bottom 145 now is folded to overlap the adjacent bottoms 157 and 158 of the auxiliary packages 137 and 144 and the bottom 124 of the front compartment 126, and is adhesively secured thereto so as to close the lower end of both the main and auxiliary packages. The flap 146, which now overlaps the side 115, is adhesively connected thereto, while the flaps 148 and 149 which overlap the upper ends of the sides 115 and 113—114 are adhesively secured to these sides when the cover is closed. The cover 147 remains open until the main compartments 126 and 127 are filled with cigarettes which, as shown, are of slightly smaller size than the standard size, and until two cigarettes 159 are positioned endwise in each of the spaced auxiliary packages 137 and 144. The flange 128 is then moved inwardly to overlap the uppermost cigarette in the compartment 127, and the flaps 132 and 143 in each of the auxiliary packages 137 and 144 respectively are folded inwardly above the flange 128. The cover is then folded over the flaps 132 and 143, and the flap 147 and tab 151 are flexed to overlap the front 111 and the tab 155. The wings 148 and 149 which are bent downwardly, so as to be adhesively connected to the adjacent sides 113 and 114—115, maintain the cover in its closed position. The cover 147, at each of its opposite sides, is formed by the weakened portions 153 with bendable and detachable sections 160 which normally overlap the cigarettes in the auxiliary compartments 137 and 144, and which, when detached from the cover and flexed upwardly, allows access to the cigarettes in the auxiliary compartments to remove the same. When a cigarette is withdrawn from one of the auxiliary compartments, the section 160 may be bent downwardly over the cigarette remaining in the compartment, so as to protect the same from dirt and moisture.

It will be seen that the cigarettes in the package or container are easily removable and of such size as to, at any time, satisfy the particular taste of the smoker. As the smaller cigarettes are sequentially and individually withdrawn from the front and rear sides, the adjacent sections 154 are arranged to be bent inwardly to overlap the cigarette immediately below the one removed, to protect the same from damage or contamination, and the front and rear sides gradually are reduced in size as the cigarettes are consumed. On the other hand, if at any time a larger size of cigarette than those con-

tained in the main package is desired, these are readily available in the auxiliary compartments 172 and 173, by raising the bendable and detachable sections 160 on the cover, and without disturbing the arrangement of the smaller cigarettes in the main package.

In Figure 22 is shown another form of pre-formed blank 160' shaped to provide a main package and an auxiliary package and essentially distinguishes from the form illustrated in Figure 16 by utilizing only one auxiliary package instead of a pair of such packages. From the blank 160' is formed the front side 161, rear side 162, and side or end 163. The front 161 has extending laterally therefrom, a wing 164 which overlaps a complementary wing 165 extending from the rear side 162 and is adhesively secured thereto in order to provide a side or end opposite to the side 163 when the package is assembled. The front wall 161 has extending downwardly therefrom, a portion 166 having spaced transverse creases 167, 168, and 169 which, when folded, form the bottom 170 and a partition 171 that separates the front and rear sides into spaced compartments 172 and 173. The side 163 has a depending portion 174 having spaced transverse creases 175, 176, and 177. The portion 174 is provided with the hinged sides 178 and 179 and a hinged flap 180. These parts, when folded along the score lines, form the auxiliary package 181 (Figure 27) which extends laterally from one side of the main package.

The rear side 162 has a hinged flap 182 which forms the bottom of the main and auxiliary packages and at its upper end has extending therefrom, a hinge or cover flap 183 provided with the lateral wings 184 and 185 and a flap 186 arranged to cover and close the top of the main and auxiliary packages.

The front and rear sides are provided with transverse vertically spaced weakened portions 167 and the vertical weakened portions 168 which, on the rear side, extend across the cover 183 and the flap 186. These weakened portions form the front and rear sides into spaced, bendable, and detachable sections 169 and the cover 183 into the bendable and removable section 190 that normally overlaps and is adhesively secured to the front side of the auxiliary package 181.

As the blank 160' is folded along the vertical and transverse score lines, the parts assume the position as shown in Figure 23, and upon further closing of the package, it will be seen that the side 174 is moved substantially parallel to the side 162, and the sides 178 and 179 are positioned adjacent the rear and front sides of the package and are adhesively secured thereto, so as to provide the auxiliary package 181. The wings 164 and 165 now overlap and are adhesively connected to form with the side 163 the opposite ends of the package (Figure 24). Incidentally, it will be noted that the side 163 also forms the outer wall of the auxiliary package 181. The portion 166 is at the same time folded to form the auxiliary bottom 170 and the partition 171. The main bottom 162 is then folded to overlap the bottom 184 of the auxiliary package 180 and the bottom 170, so as to firmly close and reinforce the lower ends of the main and auxiliary packages. The parts are now in the position shown in Figure 27. After the compartments 172 and 173 have been filled with cigarettes and two cigarettes are inserted in the auxiliary package 181, the flange 195 on the partition 171 is bent to overlap and

5 maintain the cigarettes in the rear compartment in a firm and compact position, and the flap 180 is bent over the flange 195 to cover the uppermost cigarettes in the compartments 172 and 173. The cover 183 is then closed, and the wings 184 and 185 are adhesively secured to the adjacent sides of the package. The flap 180 on the cover now overlaps the front side 161 and the hinged tab 192 extending therefrom. The cover 183 may be formed with a perforated portion 188 which is connected to the upper section 189 of the rear side 162 to provide a tab to facilitate the withdrawal of the cigarettes from the rear compartment 173. The flap 180 of the cover may 10 also be provided with a tab 194 which normally overlaps the front 161 so as to provide means for facilitating access to the cigarettes in the compartment 172. The cigarettes in the main compartments 172 and 173 are arranged to be individually and laterally removed, and the front and rear sides are reduced in size as the cigarettes are withdrawn in the same manner as in the forms of the invention previously described. The auxiliary package 181 preferably accommodates two 15 "King's size" cigarettes, and access thereto may be had by tearing off a portion of the section 190 along the score line 188 to provide a hinged flap which allows the cigarettes to be withdrawn endwise or vertically from the auxiliary package 181. 20 The section 190 may then be bent over the cigarette remaining in the auxiliary package to protect the same until it is removed.

25 It will be seen that the several forms of the invention have in common the provision of a flat package for cigarettes or similarly shaped articles in which the cigarettes are individually removed laterally from one side of the package; and in which means are provided for covering and maintaining the cigarettes remaining in the package 30 in a compact, fresh, and clean condition; and in which the front and rear sides are reduced in size as the cigarettes are withdrawn. Moreover, each package is so constructed as to be reinforced at its ends and corner portions so as to be capable of withstanding the handling to which a device of this character is ordinarily subjected. In all forms of the invention, both the inside and outside walls of the package are preferably provided with a layer of Cellophane to render the package impervious to air and moisture. The main package may also be provided with one or more auxiliary packages formed from the blank and arranged to accommodate cigarettes of the same or of different size than those contained in the main package so as to satisfy the particular taste and desires of the smoker who may, at times, enjoy a long smoke and at others, a shorter smoke.

35 When it is considered that about ninety per cent of cigarette smokers only smoke about sixty per cent of a cigarette, the waste of unsmoked tobacco becomes obvious. Accordingly, the provision of a package, such as embodied in the present invention, containing cigarettes of varying sizes will result in a substantial saving to the smoker. Moreover, the packages are neat, compact, and flat, so as to be conveniently carried in one's pocket or purse without danger of accumulating dirt caused by loose tobacco, and are so 40 constructed as to eliminate the causes that make for annoyance, inconvenience, and irritation of the smoker.

45 It is to be understood that the several forms of the invention shown and described are merely 50 illustrative of preferred embodiments, and that

such changes may be made as fall within the purview of one skilled in the art without departing from the spirit of the invention and the scope of the appended claims.

I claim:

1. A package for cigarettes and similarly shaped articles having its sides and ends closed and having a partition between its front and rear sides, said partition forming spaced compartments in which the cigarettes are arranged transversely in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear sides of the package become smaller as the cigarettes are removed.

2. A package for cigarettes and similarly shaped articles having its sides and ends closed and provided with an integral partition between its front and rear sides, said partition forming spaced front and rear compartments in which the cigarettes are arranged transversely in rows extending from the bottom to the top of the package, said partition having a flange overlapping the uppermost cigarette in the rear compartment to maintain the same firmly in a compact position, the front and rear sides of the package having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear sides of the package become smaller as the cigarettes are removed.

3. A package for cigarettes and similarly shaped articles having its sides and ends closed and having a partition between its front and rear sides, said partition forming spaced compartments in which the cigarettes are arranged transversely in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, and the upper end of the rear side having a hinged cover for closing the top of the package, said cover having a flap overlapping the upper section of the front of the package and movable outwardly relative thereto so that the uppermost section may be initially moved outwardly to allow withdrawal of the uppermost cigarette and then be bent inwardly to overlap and cover the cigarette below the one removed.

4. A package for cigarettes and similarly

shaped articles having its sides and ends closed and having a partition between its front and rear sides, said partition forming spaced compartments in which the cigarettes are arranged trans-

versely in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the top having a hinged flap overlapping the uppermost section of the front of the package and movable away therefrom so that the said uppermost section may be initially moved outwardly to allow withdrawal of the uppermost cigarette and then be bent inwardly to overlap and cover the cigarette below the one removed, and the uppermost sections on the front and rear sides of the package having means for facilitating the movement thereof relative to the package.

5. A package for cigarettes and similarly shaped articles having its sides and ends closed and having a partition between its front and rear sides, said partition forming spaced compartments in which the cigarettes are arranged transversely in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the top having a hinged flap overlapping the uppermost section of the front of the package and movable away therefrom so that the said uppermost section may be initially moved outwardly to allow withdrawal of the uppermost cigarette and then be bent inwardly to overlap and cover the cigarette below the one removed, the uppermost section in the front side of the package having a tab for facilitating the movement thereof relative to the package, and the top of the package having a perforated portion connected to the rear side and arranged to be struck out to form a tab to facilitate the bending of the uppermost section on the rear side of the package.

6. A package for cigarettes and similarly shaped articles formed from a blank folded to provide closed sides and ends, one side of the blank having an extension bent to provide a partition between the front and rear sides to form separate compartments in which the cigarettes are arranged transversely in rows extending from the bottom to the top of the package, said extension constituting a bottom for one of the compartments and said partition having a flange overlapping the other compartment to maintain the uppermost cigarette therein in a compact position, the front and rear sides of the package having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front

and rear sides of the package become smaller as the cigarettes are removed.

7. A package for cigarettes and similarly shaped articles formed from a blank folded to provide closed sides and ends, the front side of the blank having an extension bent to provide a partition between the front and rear sides to form separate compartments in which the cigarettes are arranged transversely in rows extending from the bottom to the top of the package, the front, rear, and opposite sides of the package having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear sides of the package become smaller as the cigarettes are removed.

8. A package for cigarettes and similarly shaped articles formed from a blank folded to provide closed sides and ends, the front side of the blank having an extension bent to provide a partition between the front and rear sides to form separate front and rear compartments in which the cigarettes are arranged transversely in rows extending from the bottom to the top of the package, the front, rear, and opposite ends of the package having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette in the front compartment and then arranged to be bent inwardly to overlap and cover the cigarette below the one removed, the upper free end portion of the partition having a flap extending inwardly to overlap the rear compartment to retain the cigarettes therein, each section being detachable when the cigarette immediately below the same is withdrawn so that the front and rear sides of the package become smaller as the cigarettes are removed.

9. A package for cigarettes and similarly shaped articles having its sides and ends closed and having a partition between its front and rear sides, said partition forming spaced main compartments in which the cigarettes are arranged lengthwise in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear

sides of the package become smaller as the cigarettes are removed therefrom, at least one of the opposite sides of the package having a laterally projecting portion formed to provide an auxiliary compartment extending from the bottom to the top of the package and in which the cigarettes are arranged endwise, said auxiliary compartment having a closed bottom, and the upper end of the rear side having a hinged cover for closing the top of the main and the auxiliary compartments, said cover having bendable and detachable sections to permit access to the auxiliary compartment to effect endwise removal of the cigarettes therefrom.

10. A package for cigarettes and similarly shaped articles having its sides and ends closed and having a partition between its front and rear sides, said partition forming spaced main compartments in which the cigarettes are arranged lengthwise in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear sides of the package become smaller as the cigarettes are removed therefrom, the opposite sides of the package each having a laterally projecting portion formed to provide an auxiliary compartment extending from the bottom to the top of the package and in which the cigarettes are arranged endwise, each of the auxiliary compartments having a closed bottom, and the upper end of the rear side having a hinged cover for closing the top of the main and auxiliary compartments.

11. A package for cigarettes and similarly shaped articles having its sides and ends closed and having a partition between its front and rear sides, said partition forming spaced main compartments in which the cigarettes are arranged lengthwise in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear sides of the package become smaller as the cigarettes are removed therefrom, the opposite sides of the package each having a laterally projecting portion formed to provide an auxiliary compartment extending from the bottom to the top of the package and in which the cigarettes are arranged endwise, each of the auxiliary compartments having a closed bottom, and the upper end of the rear side having a hinged cover for closing the top of the main and auxiliary compartments, said

cover having bendable and detachable sections to permit access to the auxiliary compartments to effect endwise removal of the cigarettes therefrom.

12. A package for cigarettes and similarly shaped articles having its sides and ends closed and having a partition between its front and rear sides, said partition forming spaced main compartments in which the cigarettes are arranged lengthwise in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that the front and rear sides of the package become smaller as the cigarettes are removed, the opposite sides of the package each having a laterally projecting portion formed to provide an auxiliary compartment extending from the bottom to the top of the package and in which the cigarettes are arranged endwise, each of the auxiliary compartments having a closed bottom, the upper end of the rear side having a hinged cover provided with a flap overlapping the uppermost section of the front of the package and movable away therefrom so that the said uppermost section may be initially moved outwardly to allow withdrawal of the uppermost cigarette and then be bent inwardly to overlap and cover the cigarette below the one removed, said cover closing the main and auxiliary compartments and having bendable and detachable sections arranged, when moved upwardly, to allow endwise removal of the cigarettes in the auxiliary compartments and to be bent downwardly to cover the cigarettes remaining in the auxiliary compartments.

13. A package for cigarettes and similarly shaped articles formed from a blank folded to provide closed sides and ends and having an integral partition between the front and rear sides, said partition forming separate main compartments in which the cigarettes are arranged lengthwise in rows extending from the bottom to the top of the package, the front and rear sides having transversely disposed and vertically spaced weakened portions forming bendable and detachable sections therebetween, each weakened portion being substantially in alignment with the plane of contact between two adjacent cigarettes, the section adjacent the uppermost cigarette in the front side of the package being initially movable outwardly to allow withdrawal of the uppermost cigarette and then arranged to be bent inwardly to overlap and cover the cigarette below the one removed, each section being detachable when the cigarette immediately below the same is withdrawn so that

the front and rear sides of the package are gradually reduced in size as the cigarettes are removed therefrom, one side of the package having an outwardly projecting portion formed to

5 provide an auxiliary compartment extending from the bottom to the top of the package and in which the cigarettes are arranged endwise, said auxiliary compartment having a closed bottom and an opened top, and the upper end
10 of the rear side having a hinged cover for closing the top of the main and auxiliary compartments.

14. A package for cigarettes and similarly shaped articles formed from a blank folded to
15 provide closed sides and ends and having an integral partition between the front and rear sides, said partition forming separate main compartments in which the cigarettes are arranged lengthwise in rows extending from the bottom
20 to the top of the package, the front and rear sides having transversely disposed and vertically spaced weakened portions forming bendable and detachable sections therebetween, each weakened portion being substantially in alignment
25 with the plane of contact between two adjacent cigarettes, the section adjacent the uppermost cigarette in the front side of the package being initially movable outwardly to allow withdrawal of the uppermost cigarette and then
30 arranged to be bent inwardly to overlap and cover the cigarette below the one removed, each section being detachable when the cigarette immediately below the same is withdrawn so that the front and rear sides of the package are
35 gradually reduced in size as the cigarettes are removed, one side of the package having an outwardly projecting portion formed to provide an auxiliary compartment extending from the bottom to the top of the package and in which the cigarettes are arranged endwise, said auxiliary compartment having a closed bottom and an opened top, the cigarettes in each of said auxiliary compartments being removable and the upper end of the rear side having a hinged cover
45 for closing the top of the main and auxiliary compartments, said cover having a bendable and detachable section overlapping the auxiliary compartment and arranged to be moved away therefrom to permit endwise removal of the
50 cigarettes in the auxiliary compartments from the package.

15. A package for cigarettes and similarly shaped articles having a main compartment in which the cigarettes are arranged transversely
55 in rows extending from the bottom to the top of the package, opposite sides of the package having means for singly withdrawing the cigarettes laterally therefrom, said package having spaced auxiliary compartments extending lengthwise of the package and in which the cigarettes are arranged endwise, each of said auxiliary compartments having a closed bottom and an open top, and a hinged cover for closing the top of the main and auxiliary compartments.
